UNITED STATES PATENT OFFICE.

ROBERT L. HOLLINGSWORTH, OF HATTIESBURG, MISSISSIPPI.

WAVE MOTOR.

Application filed December 23, 1922. Serial No. 608,691.

The object of my said invention is to improve wave motors of the vertically guided float type by the provision of simple and highly efficient means for converting the 5 reciprocatory motion of a float actuated by waves in a body of water, into a rotary motion.

To the attainment of the foregoing, the invention consists in the improvement as 10 hereinafter described and definitely claimed.

In the accompanying drawings, forming part of this specification:—

Figure 1 is a side elevation of the wave motor constituting the preferred embodiment of my invention.

Figure 2 is an end elevation of the motor.

Figure 3 is a top plan view of the motor.

Figure 4 is a horizontal section taken in the plane indicated by the line 4—4 of Figure 1, looking downwardly.

Similar numerals of reference designate corresponding parts in all of the views of the drawings.

Among other elements my novel motor 25 comprises a main frame adapted to be fixed in a body of water and including uprights 1 of angular form in horizontal section, and a platform 2 superimposed upon and fixed to the upper ends of the said uprights. The 30 said main frame also comprises a horizontal bar 3 interposed between and fixed to the uprights 1 at one end of the frame.

Arranged between and loosely fitting in the uprights 1 is a movable float 4 on which 35 are end anti-friction wheels 5 and side anti-friction wheels 6, the said wheels 5 and 6 being arranged to bear against the vertical edges of the uprights 1 of angular form in cross-section so as to render easy the up 40 and down movements of the float and to prevent undue wear of the float and uprights 1 incident to the movements of the float.

Appropriately fixed to and rising from 45 the float 4 is a standard 7 and pivotally connected to the said standard, and preferably capable of adjustment in virtue of its apertures 8 is a link 9. At its upper end the said link 9 is pivotally connected to the inner end of the inner arm of a walking beam 10. The said walking beam 10 is provided by preference with a plurality of apertures 11 so that it can be adjustably fulcrumed on a standard 12 supported by the 50 before mentioned frame bar 3. In virtue of the adjustment provisions referred to, the

walking beam 10 is adapted to be adjustably positioned to better accommodate the working parts of the mechanism to the size of the waves in which the float 4 is disposed. 60

Mounted on the platform 2 is a shaft 13 to which is fixed a ratchet wheel 14. The said ratchet wheel 14 is opposed to a dog 15 designed to prevent retrograde rotation of the said shaft 13, the said dog 15 being 65 backed by a spring strip 15^x of considerable length, supported on an inclined pillar block 16, and appropriately fixed at its outer end 17 thereto. Pivoted to the shaft 13 and straddling the ratchet wheel 14 is a lever 18 by which is carried a spring pressed 70 detent 19, arranged on movement of the lever 18 in one direction, downwardly or upwardly, to turn the ratchet wheel 14 and the shaft 13, and also arranged to ride idly 75 over the teeth of the ratchet wheel 14 on reverse motion of lever 18. Interposed between and pivotally connected to the lever 18 and the outer arm of the walking beam 10 is a link 20. Manifestly when the float 80 4 is moved upwardly and downwardly by the action of waves and gravity, the walking beam 10 will be powerfully rocked or oscillated with the result that considerable leverage will be exerted on the shaft 13, and said shaft will be powerfully turned step by step in one direction.

Any preferred means may be employed for taking power from the shaft 13, the means illustrated for said purpose being 85 made up of a pulley 21 fixed on the shaft, a counter-shaft 22 on the platform 2 and equipped with a pulley 23, and a belt 24 mounted on and connecting the pulleys 21 and 23. 90

It will be apparent from the foregoing 95 that my novel wave motor is at once simple in construction and reliable in operation; also, that the wave motor is free from delicate parts and is therefore well adapted to withstand the rough usage to which wave motors are ordinarily subjected. 100

I have entered into a detailed description 105 of the construction and relative arrangement of the parts embraced in the present and preferred embodiment of my invention in order to impart a full, clear and exact understanding of the said embodiment. I do not desire, however, to be understood as confining myself to the specific construction and relative arrangement of parts inasmuch as in the future practice of the invention various 110

changes and modifications may be made such as fall within the scope of my invention as defined in my appended claim.

Having described my invention, what I claim and desire to secure by Letters Patent, is:—

A wave motor comprising a plurality of spaced up-rights, a platform mounted upon the up-rights, a power shaft supported upon the platform, a horizontal bar between certain of the up-rights, a movable float within the up-rights, a vertical standard carried by the float, a link having its lower end adjustably connected with the standard, 10 a walking beam adjustably and pivotally mounted upon the horizontal bar with its inner end pivotally connected with the upper end of the link, a lever having one end

bifurcated and rotatably mounted upon the shaft, a ratchet on the shaft in the bifurcated portion of the lever, a spring detent carried by the lever for engagement with the ratchet to rotate said ratchet in one direction upon downward movement of the lever, a spring pressed dog retaining said ratchet against movement, and a second link 20 forming loose connection between the outer end of the lever and the outer end of the walking beam whereby vertical movement of the float between the up-rights in one direction will impart movement to said shaft. 25

Witness my signature this 23rd day November 1922.

ROBERT L. HOLLINGSWORTH.
